UNITED STATES PATENT OFFICE.

JOSEPH EBERHARD, OF NEW YORK, N. Y.

DIE-PLATE FOR EMBOSsing-MACHINES.

SPECIFICATION forming part of Letters Patent No. 630,672, dated August 8, 1899.

Application filed March 31, 1899. Serial No. 711,265. (No model.)

To all whom it may concern:

Be it known that I, JOSEPH EBERHARD, of the city of New York, borough of Brooklyn, in the county of Kings and State of New York, have invented a new and Improved Die-Plate for Embossing-Machines, of which the following is a full, clear, and exact description.

The invention relates to embossing-machines; and its object is to provide a new and improved die-plate arranged to securely hold a die or dies in place and to permit of conveniently and quickly adjusting the die without the aid of skilled labor and to obtain accurate registration of the male and female dies, so as to insure first-class work.

The invention consists of novel features and parts and combinations of the same, as will be fully described hereinafter and then pointed out in the claims.

A practical embodiment of my invention is represented in the accompanying drawings, forming a part of this specification, in which similar characters of reference indicate corresponding parts in all the views.

Figure 1 is a face view of a die-plate in position on the embossing-press with two dies secured to the plate. Fig. 2 is an edge view of the same. Fig. 3 is a transverse section of the same on the line 3 3 in Fig. 1 and with the male and female dies in engagement, and Fig. 4 is an enlarged plan view of the improvement on the line 4 4 in Fig. 1.

In embossing-machines heretofore constructed the dies were glued or cemented to cardboard plates in such a manner as to register with each other when brought opposite in the embossing-machine by the usual mechanism employed for the purpose. One of the dies, the female die, is usually of metal, with the design engraved thereon, and the other (or the male) die is usually of celluloid or like material. It requires considerable time and skilled labor to glue the dies in position on the plates so that they register accurately when making an impression, and it takes considerable time for the glue or other binding substance used to harden and set before the plates can be placed in position in the embossing-machine. The dies thus arranged on the plates are liable to get out of register owing to shrinkage or expansion of either of the cardboard plates carrying the dies, and if this

takes place one die has to be reset by loosening it on its plate, then shifting it to the proper registering position, and then regluing or cementing it to the plate. It has also happened that a die fastened to the plate in the manner described became accidentally loose from its plate and dropped into the working parts of the machine, thereby injuring the latter to a considerable extent before the machine could be stopped.

With the improvements presently to be described in detail the operator is enabled to securely fasten the metal die in proper position on the plate and to instantly shift the metal die and bring it into accurate registration with the celluloid die.

As illustrated in Fig. 1, two female dies A are shown on a plate B, attached to a press or embossing-machine C in the usual manner, preferably by setting the lower edge of the plate on a flange D and engaging the upper end by clamps E, as is plainly indicated in Figs. 1 and 2. The male dies F for the female dies A on the plate B are glued or otherwise fastened to a die-plate G to be set in the press in such a manner that when the press is actuated the corresponding dies A and F register with each other to make the desired impression.

Each of the dies A is provided with countersunk apertures A', loosely engaged by screws H, each screwing into one of a series of tapped or threaded apertures B', arranged all over the plate B in close proximity to each other, as indicated in Figs. 1, 3, and 4. The head H' of the screw H extends in the countersink of the aperture A' to be below the face of the die, as is plainly indicated in Fig. 4, and said head engages the bottom of the countersink to securely fasten the plate A to the plate B upon screwing up the screw H. As the threaded apertures B' are very close together, it is evident that when the die A is placed in position on the plate B then the apertures A', which are considerably larger than the apertures B', embrace a number of such apertures B', as indicated on the die A at the left in Fig. 1, so that the screws can be readily screwed into the apertures B', registering with the apertures A' at the time to secure the die in place and at the same time allow a shifting of the die in any desired direc-

tion before finally fastening the die in place on the plate to bring the design on the die in proper register with the male die F on the other plate G.

5 It is evident from the foregoing that in case the dies A and F are out of register for any cause whatever the operator by loosening the screws H can readily shift the die A to again bring the two dies A and F in register with-
10 out removing the die from the plate B. When the desired registration is obtained, the screws H are again screwed up to securely fasten the die in place. It is further evident that the dies A are not liable to become accidentally
15 detached from the plate B while the press is in use, and dies of various sizes and with differently-spaced apertures A' can be used on the same plate B, as each aperture A' is sure to register with at least one of the apertures
20 B' to permit of inserting the screw H to fasten the die in the proper place.

Having thus fully described my invention, I claim as new and desire to secure by Letters Patent—

25 1. An embossing-machine provided with a die-plate having a series of threaded apertures arranged all over the plate in close proximity to each other, dies having apertures larger than the apertures in the die-plate
30 whereby when the die is placed in position on the plate, the apertures in the said die each embrace a plurality of the apertures in the

plate, and a screw passing loosely through each aperture in said die and screwing into one of the threaded apertures in the plate, 35 the heads of the screws engaging the die and securing the same in place, substantially as shown and described.

2. A die-plate arranged for attachment to a press or embossing-machine and having a 40 series of threaded apertures arranged close to one another and distributed all over the plate, a female die having circular countersunk apertures located at two or more corners of the die, the said apertures being larger 45 than the apertures in the die-plate whereby when the die is placed in position on the plate, the circular apertures in the die each embrace a plurality of the apertures in the plate, and screws passing loosely through said apertures in the die, and each screwing into one of said threaded apertures in the plate, the construction permitting a ready shifting of the die in any desired direction, the heads of the screws extending in the countersinks of 50 the apertures and adapted when screwed up to engage the bottoms of the countersinks to secure the die in place substantially as shown and described.

JOSEPH EBERHARD.
